UNITED STATES PATENT OFFICE

150,396

DESIGN FOR A TANDEM ROAD ROLLER

Ola L. Berby, Duluth, Minn., assignor to Clyde Iron Works, Inc., Duluth, Minn., a corporation of Minnesota

Application April 13, 1946, Serial No. 128,562

Term of patent 7 years

(Cl. D14—3)

To all whom it may concern:

Be it known that I, Ola L. Berby, a citizen of the United States, residing at Duluth, county of St. Louis, and State of Minnesota, have invented a new, original, and ornamental Design for a Tandem Road Roller, of which the following is a specification, reference being had to the accompanying drawing, forming part thereof.

Figure 1 is a perspective view of my tandem road roller, showing my new design;

Figure 2 is an elevational view showing one side thereof;

Figure 3 is an elevational view showing the other side thereof; and

Figure 4 is a top plan view of the same.

The characteristic features of my design reside in the portions shown by means of full lines in the drawing.

I claim:

The ornamental design for a tandem road roller, as shown and described.

OLA L. BERBY.
